Inventor:

Sebastian Lay

UNITED STATES PATENT OFFICE.

SEBASTIAN LAY, OF LA PORTE, INDIANA.

HEAD-REST.

SPECIFICATION forming part of Letters Patent No. 245,639, dated August 16, 1881.

Application filed February 18, 1881. (No model.)

To all whom it may concern:

Be it known that I, SEBASTIAN LAY, of La Porte, in the county of La Porte and State of Indiana, have invented certain Improvements 5 in Head-Rests, of which the following is a specification.

In this invention I have devised a portable device whereby the forehead may be supported when the user leans forward, and, in 10 combination therewith, a support for the arms, so that the forward inclination of the body may be rendered easy and comfortable, and at the same time the device be steadied without being affixed stationarily to the seat. It is de- 15 signed more especially for night travel in railroad-cars, but may be used by invalids and others who cannot rest by reclining backward or lying down.

The device consists, when briefly stated, in 20 a cushioned rest, suitable to receive the forehead, and a standard, either single or double, supporting the same from the floor.

It also consists in the combination, with this 25 rest and standard, of a suitable platform or rest for the arms, whereby the device is steadied and the weight of the body in the forward posture is taken from the head and devolved upon the arms.

The accompanying drawings show, at Figure 1, the device in use; at Fig. 2, a back view of the device; at Fig. 3, a section through the head-rest and its fastening to the standard, and at Fig. 4 a section of the supporting-standard.

35 In the drawings, A A' A² are telescoping sections of tubing, which form the standard of my device. The lower one is preferably provided with a blunt point at the bottom to prevent slipping upon the floor or carpet. The 40 sections of the standard are adjustable within each other, and are held, when adjusted, by the spring-catches *a*, entering perforations *a'*, the former upon the larger section, A or A', and the latter in the smaller section, A' or A². Upon the other side from the catch *a* is another catch, *a*², designed to enter a groove or slot in the smaller section of the standard, so 45 that the sliding of the one section within the

other may be without any turning or twisting, the perforations *a'* being thus kept in line with 50 the catch *a*. One side of this groove or slot is shown at *a*³.

In Fig. 4, I have illustrated the adjustability of the sections A and A'; but the same figure shows that of sections A' and A², as the construction is the same in both cases.

The forehead-rest B, which is preferably cushioned, is hinged to the section A², as shown at *b*, so it may be rocked to a position agreeable to the user.

55 The arm-rest C is preferably of such dimensions as to afford a bearing-surface for the forearm at either side of the standard, and it may be upholstered also.

The head-rest is detachably held to its hinging device *b* as follows: A plate, *d*, is provided with two ears, *e*, which project down and are pierced to receive the pivot of the hinge, as shown at Fig. 3. When the head-rest is applied to the standard this plate *d* is 70 slipped between two overlapping and retaining pieces, *d'*, secured to the back of the head-rest and positioned to fit said plate. The arm-rest is also detachably secured upon the standard by means of a similar plate, *d*, upon the 75 standard and similar overlapping plates *d'* upon the rest. This latter plate *d* is perforated, as is also the arm-rest itself, to permit the passage of the section A².

The arm-rest is secured by its fastenings, 80 which are located upon section A' of the standard, before section A² is inserted within said section A', and removed after said section A² is withdrawn.

The method of using the device is fully shown 85 in Fig. 1.

A double standard, adapted to span the lap of the user, may be used, if desired; or the standard may be constructed with a forked lower portion, which may span the lap in like 90 manner. The arm-rest may be provided with devices whereby it may be inclined to suit the fancy or ease of the owner. All these changes are within the spirit of my invention.

The device may also be used with the body 95 in an erect or slightly back of the erect post.

ure by simply inclining the head forward, as the standard permits use either at an incline or vertical position.

To hold the rests upon their dovetail fastenings, above described, I provide them with side spring-actuated catches, *m*, as shown in Fig. 3, or equivalent devices.

When not in use the apparatus may be taken apart and packed away in compact form.

10 I claim—

A standard extending upward from the floor, a forehead-rest at the top, and an arm-rest at the center of the standard, all combined and constructed substantially as shown, and adapted to sustain the weight of a person leaning thereon. 15
